UNITED STATES PATENT OFFICE.

LEO A. MILLER, OF PLAINFIELD, NEW JERSEY, ASSIGNOR TO G & G ATLAS SYSTEMS, INC., OF NEW YORK, N. Y., A CORPORATION OF NEW YORK.

CASH CARRIER.

Application filed September 7, 1923. Serial No. 661,369.

To all whom it may concern:

Be it known that I, LEO A. MILLER, a citizen of the United States, residing at Plainfield, in the county of Union and State of New Jersey, have invented a certain new and useful Improvement in Cash Carriers, of which the following is a specification.

The invention relates to the cylindrical receptacles or shells employed in pneumatic cash-carrier systems, and more particularly to means for attaching the felt heads to the ends of such carriers.

The object of the invention is to provide simple, economically constructed and easily assembled means whereby the head is reliably secured to the shell, such means adapted to serve in reinforcing the end of the shell and also presenting a plane surface on the interior of the shell, free from inwardly projecting obstructions with which coins and the like are liable to engage, thus insuring against annoyance due to such engagement and the consequent non-delivery of a portion of the contents when the carrier is opened.

A further object is to provide for releasing the head when required and permitting separation of the parts for the substitution of a new head or other repairs.

The invention consists in certain novel features and details of construction and arrangement by which the above objects are attained; to be hereinafter described and claimed.

The accompanying drawings form a part of this specification and show the invention as it has been carried out in practice.

Figure 1 is a side elevation of the improved carrier, partly in axial section.

Figure 2 is a corresponding end view.

Figure 3 is a transverse section taken on the line 3—3 in Figure 1.

Figure 4 is an end elevation of the shell alone.

Figure 5 is a face view of a disk and its tongues forming the main member of the fastening device.

Figure 6 is a cross-section taken on the line 6—6 in Figure 5.

Figure 7 is an edge view of the disk.

Figure 8 is a face view of a washer adapted to be engaged by the tongues.

Figure 9 is a cross-section taken on the line 9—9 in Figure 8.

Figure 10 is an edge view of the washer.

Figure 11 is a section corresponding to a portion of Figure 1, taken on a plane indicated by the lines 6—6 and 9—9 in Figures 5 and 8 respectively.

Similar reference numerals indicate the same parts in all the figures.

The body of the carrier comprises two cylindrical cups or shells 12 and 13 received one within the other with their closed ends, only one 14 of which is shown, oppositely arranged, having the usual large opening 15 for the introduction and delivery of the contents, and held against axial displacement by the usual or any approved means, not shown.

Each end is provided with diametrically located perforations as at 16, preferably equidistant from the centre. The main locking members comprise each a circular disk 17 of a size to cover completely the inner face of the adjacent ends. It is cut by suitable dies to produce two oppositely extending slots 18 the metal of which is bent at a right angle to the face of the disk to form two projecting tongues 19 adapted to be thrust through the perforations 16 from the interior of the shell and project outwardly from its end. The disk is introduced through the opening 15.

Upon the tongues is placed a correspondingly perforated thin flexible circular apron or skirt 20, adapted to perform its usual packing functions, and the similarly perforated head 21 of felt having a central circular cavity 22 in its outer face, in which is received a metal washer 23 having holes 24 through which the extremities 25 of the tongues protrude.

By supporting the shell on a suitable anvil, not shown, introduced through the opening 15 against the disk 17, the protruding extremities 25 are bent downwardly in opposite direction upon the outer face of the washer 23 and clinched thereon by the application of a suitable tool. This operation draws the disk 17 snugly against the adjacent inner face of the end 14, thus strongly reinforcing the latter, and forces the apron 20, head 21 and washer 23 into close contact with each other and with such end, thus reliably securing the parts together without danger of accidental separation, and permitting the shells to be rotated as usual relatively to each other in opening or closing the carrier.

To provide spaces for the reception of the bent extremities 25 of the tongues and permit the outer face of the washer 23 to present an approximately plane surface, the 5 washer is formed with grooves or recesses 26 extending outwardly from the holes 24, adapted to receive the folded-over extremities.

Any slackness due to wear or other cause 10 may be taken up by a re-application of the clinching tools.

To separate the parts it is only necessary to insert the point of a tool, not shown, beneath the bent extremities 25 and by a prying 15 action straighten the extremities sufficiently to permit the withdrawal of the washer 23, head 21 and apron 20, the disk 17 with its tongues 19 may then be withdrawn from the interior of the carrier.

20 To facilitate the folding of the tongues upon the washer in the locking operation, the extremities 25 are formed with a slight initial bend as at 27.

It will be noted that the disk 17 practically 25 covers the entire interior face of the end 14, and as its periphery is unbroken no recesses or cavities are offered in which a coin or other article can lodge, and also that the inner face of the disk has no projecting 30 members, such as the usual bolt-heads or bars, with which the contents of the carrier can engage.

The fastening device is extremely simple 35 and economical, comprising essentially only the two members 17 and 23; the operation of assembling is easily performed; the shell-ends are reinforced to resist the battering shocks to which they are subjected in service; and the engagement of the assembled 40 parts is eminently reliable while permitting separation when required.

I claim:

1. In a carrier of the character set forth, 45 a cylindrical shell having a closed end provided with perforations, a circular disk covering the entire interior face of such end and having tongues extended through such perforations, a head through which said tongues extend, and a washer in said head having holes receiving the extremities of 50 said tongues, the latter adapted to engage said washer by bending and clinching such extremities upon the outer face of said washer.

55 2. In a carrier of the character set forth, a cylindrical shell having a closed end provided with perforations, a circular disk having an unbroken periphery, covering the entire interior face of such end and having integrally formed tongues extended through

such perforations, a head through which said tongues extend, and a washer in said head having holes receiving the extremities of 65 said tongues, the latter adapted to engage said washer by bending and clinching such extremities upon the outer face of said washer.

3. In a carrier of the character set forth, a cylindrical shell having a closed end provided with perforations, a circular disk covering the entire interior face of such end and having tongues extended through such perforations, a head through which said tongues extend, and a washer in said head having holes receiving the extremities of 70 said tongues and recesses adjacent such holes, said tongues adapted to engage said washer by bending and clinching such extremities upon the outer face thereof and into such recesses.

4. In a carrier of the character set forth, the combination of a body portion having an inner retaining member located therein at the end thereof, the said member having 75 prongs stamped out therefrom, the said prongs extending through a head portion located adjacent the end of said body portion, the said head portion having a recess provided with a perforated outer retaining member, the ends of said prongs adapted to 80 be bent down upon the said outer retaining member.

5. In a carrier of the character set forth, the combination of a body portion having an inner retaining member located therein 85 at the end thereof, the said member having prongs stamped out therefrom, the said prongs extending through a head portion located adjacent the end of said body portion, the said head portion having a recess 90 provided with a perforated outer retaining member, the ends of said prongs being adapted to be bent down in opposite directions upon the said outer retaining member.

6. In a carrier of the character set forth, 100 the combination of a body portion having an inner retaining member located therein at the end thereof, the said member having prongs stamped out therefrom, the said prongs extending through a head portion located adjacent the end of said body portion, the said head portion having a recess 105 provided with a perforated outer retaining member, the ends of said prongs adapted to be bent down upon the said outer retaining member, the latter having recesses into 110 which the bent down ends of said prongs fit.

In testimony that I claim the invention above set forth I affix my signature hereto.

LEO A. MILLER.
